UNITED STATES PATENT OFFICE.

CARL F. KIHN, OF NEW YORK, N. Y.

BOTTLE.

SPECIFICATION forming part of Letters Patent No. 662,149, dated November 20, 1900.

Application filed August 9, 1900. Serial No. 26,376. (No model.)

To all whom it may concern:

Be it known that I, CARL F. KIHN, a citizen of the United States, residing in the borough of Brooklyn, in the city and State of New York, 5 have invented a certain new and useful Improvement in Bottles, of which the following is a specification.

The main object of the invention is to avoid the possibility of refilling, the importance of 10 which is widely recognized. My invention attains this by a construction which is durable and reliable and without any metallic parts. It may be all of glass except an 15 inclosed cork and an ordinary tight-stopping cork. Metal is objectionable from its influence on many important kinds of liquids. I make the bottle in three parts, joining them 20 permanently and neatly by screw-threads and white-lead or analogous cement which will exert no objectionable influence. Within 25 the neck thus compoundly formed I inclose a loosely-fitted cork and a weight, the cork being preferably cylindrical and the weight spherical. The weight is over the cork when 30 the bottle stands upright and is sufficient to force the cork down in opposition to its buoyancy. A tight annular seat is provided below, against which the cork may make a sufficiently tight joint to insure against refilling 35 within any practicable time. When the bottle is inverted, the weight is of no effect, and then the buoyancy of the cork asserts itself and holds the cork against the seat. The liquid can be poured out from the bottle at 40 any time by the ordinary modes of tilting and reversing, the pressure of the liquid in the interior of the bottle forcing away the cork. The construction provides a great number of small crooked passages, the aggregate area of 45 which is sufficient to allow a free flow of the liquid in escaping. I provide special means for venting the passages. The venting is ample and yet so arranged that no wire or other device can be introduced to defeat the 50 action. The device attains ease of filling by the proper parties at first, a liberal flow filling the whole terminal orifice, and gives all the immunity against fraud which is afforded by the most secure of the previously-known devices. My venting-apertures in connection 55 with a longitudinal chamber provided by an encircling ridge in the interior insure a free

communication with the interior of the bottle for the admission of air through each or all of the passages.

The accompanying drawings form a part 55 of this specification and represent what I consider the best means of carrying out the invention.

Figure 1 is a central vertical section on the 60 line *w w* in Fig. 2. Fig. 2 is a plan view, partly in horizontal section on the line *x x* in Fig. 1. Fig. 3 is a horizontal section on the line *y y* in Fig. 1. The remaining figures show certain portions removed. Fig. 4 is a 65 section on the line *z z* in Fig. 3 seen from the left, and Fig. 5 is a top view.

Similar letters of reference indicate like parts in all the figures where they appear.

The three parts of the bottle may be all 70 made of glass of the same or different colors, according as the taste or a desire to readily distinguish the bottles may dictate. Certain portions of each will be indicated when necessary by supernumerals.

A is the body of the bottle, A' an offset or shoulder, and A² a short neck screw-threaded on its exterior and shaped at its top to form an annular seat to receive the cork.

B is the innermost of the two permanent 80 attachments. Its upper end is closed. Its main length is liberally perforated and provided on its exterior with longitudinal ribs B', which insure its being held concentrically within the exterior part. The exterior of the 85 lower end of this part B is equipped with a projection B², the purpose of which will presently appear. The interior of the lower end is screw-threaded to match the screw-threads on A'.

C is the exterior piece. Its interior is open 90 throughout. Its upper end may receive a cork with any more or less elaborate fastenings which may be required or expedient to serve all the uses of an ordinary bottle-mouth. 95 The slightly-tapered interior matches upon the correspondingly-tapered ribs B'. A recess c at the lower edge matches on the projection B² and insures that the parts B and C are properly related.

In applying the parts together the ball D 100 of glass is introduced into the top of the interior of B and a loosely-fitted cork E is applied below it. The length of this cork E added to

the diameter of the ball D so nearly fills the length of the hollow interior of B that when the parts are in place there is only sufficient play lengthwise to allow the cork E to move 5 from the seat A² enough to provide a free escape of the liquid in pouring out. The pouring out is performed in the ordinary manner. Any attempt to introduce the same or any other liquid into the bottle is frustrated by 10 the cork which moves to its seat by the gravity of itself and the added ball when the bottle is upright and moves to its seat by its property of flotation when the bottle is inverted.

15 A series of holes c' c² c³ c⁴ are produced in the outer neck C above the cork, which provide for the free ingress and egress of air to insure the venting of the passages. The interior of C is formed with a guard-ridge C', 20 which extends around these apertures and makes a free passage, joining the several small apertures together in the interior. A liberal longitudinal orifice b is provided in the vessel B, which coincides with these vent- 25 apertures b, and a series of other large apertures b' allow a sufficiently free motion of the fluid radially outward when the bottle is being emptied. After the liquid has moved outward through these apertures b and b' it 30 can move longitudinally through the thin and nearly continuous annular space between B and C and uniting beyond the end of B flow out through the mouth of C in the same manner as liquid flows from an ordinary bottle. 35 Besides these there are small apertures b² produced in the surface along the entire mid-length of the part B.

When through a fraudulent desire an attempt is made to use the bottle and its label 40 to receive other and inferior liquids to be sold as the genuine and an attempt is made to refill the bottle, my construction effectually defeats the effort. If the bottle is in the upright position, the cork E is held down by the weight 45 D upon the rim A². In this condition there may be leakage past the cork serving as a lightly-seated valve; but the flow of liquid into the bottle through such leakage would be too slow to be ever practiced as a means 50 of promoting fraud. If the bottle is inverted, the cork floats and closes the joint in a similar manner, with the further difficulty that the air in the bottle would forbid the liquid

entering even by leakage, and in any position the entrance of liquid through the small 55 apertures b² would further hasten and more strongly press the cork to its seat.

The cemented junctions are inseparable after the cement has fully hardened, so that the parts A, B, and C cannot be separated, 60 but will serve indefinitely afterward as an integral structure.

When the body A of the bottle is square, as shown, I prefer that the pouring shall be done with one of the angles uppermost. With 65 a square form or any other form of bottle in which there is a certain edge or face to lie uppermost in the pouring I locate the apertures c' c², &c., on the side which is to be thus presented uppermost.

Modifications may be made without departing from the principle or sacrificing the advantages of the invention. The taper of the interior of the outer shell C and of the matching surfaces of the longitudinal ribs B' may 75 be varied within wide limits or may be omitted altogether.

I use the term "bottle" to mean any analogous vessel—as vial, jug, demijohn, or the like.

I use the term "cork" to indicate the device E of whatever material. It is essential that it shall be light, so as to float, and not subject to corrosion by the liquid, and so formed that it can move to and from the seat and serve as a floating valve.

I claim as my invention—

A bottle having a valve-seat on the body adjacent to the neck and a neck in two separately-produced pieces which may be all of glass, arranged one within the other the innermost perforated laterally, on many sides, and the outermost perforated at the points c', c², and equipped with a guard-ridge C' forming a longitudinal passage connecting such perforations, in combination with a floatable 95 valve and a loosely-connected weight, all arranged for joint operation substantially as herein specified.

In testimony that I claim the invention above set forth I affix my signature in presence of two witnesses.

CARL F. KIHN.
